FINGER RING PROTECTOR

Agatha H. Starolis, San Francisco, Calif.

Application October 30, 1951, Serial No. 253,920

3 Claims. (Cl. 224—5)

1

The present invention relates to improvements in a finger ring protector. It consists of the combinations, constructions, and arrangement of parts, as hereinafter described and claimed.

It is a well-known fact that many people, when washing their hands, or performing arduous tasks, remove their finger rings in order to preclude the latter from becoming soiled or abraded. This often leads to the rings being misplaced, and, indeed, often lost.

Accordingly, the cardinal object of this invention is to provide a finger ring protector, which may be secured to an individual, for instance around the wrist or neck, to which the ring may be removably attached. Thus, in the event that a person forgets about the ring, for example after washing the hands, the ring will not be left behind.

Moreover, the ring protector may be worn by a person, such as a factory employee, while working for a considerable length of time. It affords protection against misplacement, or insecurity, of leaving finger rings in a pocket, or a pocket-book, especially when the latter is left out of sight of the owner. It provides security for the rings of factory workers, waitresses, travellers, etc. Many other uses for my finger ring protector will be pointed out as the specification proceeds.

Other objects and advantages will be mentioned in detail, and the novel features of the invention will be set forth in the claims hereunto appended.

Drawings

For a better understanding of my invention, reference should be had to the accompanying drawing, forming part of this application, in which:

Figure 1 is an enlarged elevational view of my finger ring protector in detached position;

Figure 2 is a similar view, with the flexible securing member formed into a loop, and further showing a finger ring supported on a hook of the protector; and

Figure 3 is a fragmentary view, which corresponds to a portion of Figure 2, but disclosing the parts arranged to guard against accidental displacement of the finger ring from the supporting hook.

While I have shown only the preferred form of my invention, it should be understood that various changes, or modifications, may be made within the scope of the annexed claims without departing from the spirit thereof.

2

Detailed description

Referring now to the drawing, it will be noted that my finger ring protector includes three principal parts, namely: a hook A, flexible securing member B, and a jump or round ring or clasp C. These parts will be set forth in detail.

In its structural features, the hook A is made of resilient or spring-like material and defines a pair of coacting legs 10 and 11, which are interconnected at their bottoms by a yielding loop 12. The legs have intermediate portions 10a and 11a, respectively, arranged adjacent each other, which may be spread apart due to the resilient or spring-like character of the material from which the hook is fashioned.

As clearly shown, an upper catch section 10b of the leg 10 is free, and projects upwardly and outwardly at an inclined angle relative to an upper end section 11b of the other leg to form a catch A. Thus, a downwardly-converging throat 14 is defined between these two upper sections for the purpose hereinafter mentioned. The free tip end of the end 10b is provided with a ball or protrusion 15 thereon, which is disposed at a predetermined distance from the upper section 11b of the leg 11. Furthermore, the lower section 10c of the leg 10 is bulged outwardly to a preselected extent and merges into the loop 12 of the hook.

For the purpose of illustration, the flexible securing member B has been disclosed as being formed from a chain. It will be appreciated, of course, that a large variety of materials and styles may be resorted to insofar as this member is concerned. The length of the member B may vary, as suggested by the break lines 16 in Figures 1 and 2. In certain cases, this member should have a length to encircle a person's wrist, while in other situations the member should extend around a person's neck.

It will be seen that the securing member B has one end thereof attached at 17 to the upper section 11b of the hook leg 11, while the jump or round ring C is connected to the opposite end of this securing member. The jump ring has an opening 18 of sufficiently large diameter for allowing this ring to be introduced over the ball 15, and then advanced along the legs 10 and 11 in succession until the jump ring encircles the securing member B, thereby forming a loop B' in the latter, as suggested in Figure 2 of the drawing. This loop may encircle a person's wrist or neck.

Assuming that a person desires to protect a finger ring D against being misplaced or lost, a peripheral section thereof may be inserted readily

into the throat 14, and then this ring pushed downwardly, with the ball 15 and the leg 10 passing upwardly through the opening 19 of the finger ring. Quite obviously, the adjacent intermediate portions 10a and 11a of the hook may be spread apart until the finger ring is supported on the hook loop 12, as shown in Figure 2. Of course, the portions 10a and 11a will snap back toward one another as soon as the ring D moves downwardly into the looped bottom of the hook.

With the parts now arranged in the manner shown in Figure 2, the upper catch section 10b is depressed under some pressure toward the upper section 11b of the attached leg. Now the jump or round ring is lowered over the upper sections of both legs in encircling relation therewith to provide a clasp therearound, as clearly shown in Figure 3. Upon release of pressure on the ball 15, the catch section 10b will spring outwardly, preventing the jump ring from slipping upwardly over the ball 15. The latter contacts with the section 10b in forming a shoulder 20 to resist the jump or round ring from being pulled in an upward direction over the catch.

Particular attention is called to the fact that the bulged section 10c is separated from the lower section 11c of the leg 11 at a distance greater than the internal diameter of the jump or round ring C, whereby this ring will be limited in slipping downwardly when the ring C encircles the two legs of the hook, thereby preventing the jump or round ring from sliding accidentally off the hook.

In the event that the jump or round ring C should become unfastened from the catch section 10b, it will pass over the flexible securing member B, and the wearer's attention will be attracted by a slight tug or pull. This will be especially true when a finger ring is carried by the hook, since its weight will cause this ring and the hook to gravitate downwardly, resulting in pulling the securing member B through the jump or round ring.

It will be appreciated that the protector may be made from precious metal, or otherwise. For providing the securing member B, chains of different widths may be employed, and other parts made to produce a balanced and attractive article. When the member B forms a neck-chain, the protector may be worn under the clothing, affording concealment of valuable finger rings. Moreover, these neck-chains may be wrapped around the wearer's wrist, or shorter chains provided for encircling the wrists of the wearer with comfort.

Of the many individuals for which the finger ring protectors are designed, I wish to mention the following by way of example: factory workers, waitresses, counter girls, nurses, office workers, travellers, housewives and club women. Obviously, I do not desire to be limited in this respect.

The protector not only serves to guard against misplacement and loss of finger rings, but affords security on persons, such as factory workers, when finger rings while being worn are a hazard of safety regulations and precautions. It affords security to travellers who prefer their valuable finger rings to be on their person, rather than placed in a pocketbook or some other receptacle used during travelling. This is especially true while the travellers are sleeping aboard trains and other means of transportation. The hook could be made wide enough to have the owner's name displayed thereon.

I claim:

1. In a finger ring protector of the character described: a resilient hook defining a pair of coacting legs, which are interconnected by a loop; these legs having intermediate portions arranged adjacent to each other, which may be spread apart; an elongated flexible securing member having one end attached to an upper section of one of the legs; the upper section of the other leg being free, and projecting outwardly relative to the attached leg to form a catch; the hook being made to support a finger ring, or the like; and a clasp connected to the opposite end of the securing member; the clasp having an opening therein sufficiently large for allowing this clasp to be introduced over the catch, and then advanced along the legs in succession until the clasp encircles the securing member, thereby forming a loop in the latter; the catch being made to be depressed under pressure toward the upper section of the attached leg, and into a position in which the clasp may be lowered over the upper sections of both legs in encircling relation therewith to preclude accidental removal of the finger ring; the free end of the catch section being spaced laterally from the upper section of the attached leg by a distance exceeding the greatest width of the opening in the clasp so as to normally prevent accidental slippage of the clasp upwardly over the catch.

2. In a finger ring protector of the character described: a resilient hook defining a pair of coacting legs, which are interconnected by a loop; these legs having intermediate portions arranged adjacent to each other, which may be spread apart; an elongated flexible securing member having one end attached to an upper section of one of the legs; the upper section of the other leg being free, and projecting outwardly relative to the attached leg to form a catch; the hook being made to support a finger ring, or the like; and a clasp connected to the opposite end of the securing member; the clasp having an opening therein sufficiently large for allowing this clasp to be introduced over the catch, and then advanced along the legs in succession until the clasp encircles the securing member, thereby forming a loop in the latter; the catch being made to be depressed under pressure toward the upper section of the attached leg, and into a position in which the clasp may be lowered over the upper sections of both legs in encircling relation therewith to preclude accidental removal of the finger ring; the free end of the catch section being spaced laterally from the upper section of the attached leg by a distance exceeding the greatest width of the opening in the clasp so as to normally prevent accidental slippage of the clasp upwardly over the catch.

3. In a finger ring protector of the character described: a resilient hook defining a pair of coacting legs, which are interconnected by a loop; these legs having intermediate portions arranged adjacent to each other, which may be spread apart; an elongated flexible securing member having one end attached to an upper section of one of the legs; the upper section of the other leg being free, and projecting outwardly relative to the attached leg to form a catch; the hook being made to support a finger ring, or the

like; and a clasp connected to the opposite end of the securing member; the clasp having an opening therein sufficiently large for allowing this clasp to be introduced over the catch, and then advanced along the legs in succession until the clasp encircles the securing member, thereby forming a loop in the latter; the catch being made to be depressed under pressure toward the upper section of the attached leg, and into a position in which the clasp may be lowered over the upper sections of both legs in encircling relation therewith to preclude accidental removal of the finger ring; the free end of the catch section being spaced laterally from the upper section of the attached leg by a distance exceeding 15 the greatest width of the opening in the clasp so as to normally prevent accidental slippage of

the clasp upwardly over the catch; the lower sections of the two legs being separated from each other at a distance exceeding the greatest width of the opening in the clasp, whereby the latter will be limited in slipping downwardly when the clasp encircles the two legs of the hook, thereby preventing the clasp from accidentally sliding downwardly off the hook.
